UNITED STATES PATENT OFFICE.

CLARENCE J. RODMAN, OF WILKINSBURG, PENNSYLVANIA, ASSIGNOR TO WESTINGHOUSE ELECTRIC & MANUFACTURING COMPANY, A CORPORATION OF PENNSYLVANIA.

PROTECTIVE APPARATUS.

Application filed April 28, 1923. Serial No. 635,402.

My invention relates to protective apparatus for tanks or containers, and it has particular relation to valve structures that may be employed in connection with transformers, circuit breakers or other electrical apparatus.

One object of my invention is to provide a simple and efficient valve structure that may be automatically controlled to connect the interior of a tank to the atmosphere in accordance with the pressure within the tank.

A second object of my invention is to provide a mechanism of the character above described that is controlled in accordance with the height of a column of liquid that is a measure of the pressure in the tank.

A further object of my invention is to provide a valve mechanism that is operated by a float to open a vent in a containing vessel when the pressure in the tank varies from atmospheric pressure by predetermined values.

In the operation of transformers, circuit breakers and other electrical apparatus in which insulating oils are employed for the purpose of cooling the parts of the electrical devices, it has been found advisable to isolate the surface of the oil from contact with the atmosphere in order to prevent oxidation of the oil and the absorption of moisture from the air.

It has been found that explosions have occurred in connection with enclosed electrical apparatus by reason of the formation of highly explosive compounds or mixtures as a result of arcs below the surface of the oil. The formation of such explosive mixtures is prevented if oxygen is excluded from the interior of the tanks.

The exclusion of oxygen is of advantage also, in that "sludging", which results from oxidation of the oil, is prevented. Any moisture that may be present in the air within the tanks of transformers of usual construction is absorbed by the oil, and its insulating properties are correspondingly diminished.

In accordance with the present invention, I provide a valve mechanism that is controlled in accordance with the height of a column of liquid to open or to close a vent in the tank in accordance with the

pressure therein. When the pressure in the tank is below atmospheric pressure, air is drawn into the tank through a compartment in which a suitable deoxidizing and dehydrating material operates to remove substantially all oxygen and moisture from the air, permitting substantially nitrogen only to enter the tank. The interior of the tank is connected to the atmosphere when the pressure in the tank exceeds a predetermined value or is below a second predetermined value.

65 In the accompanying drawing,

Figure 1 is a view, partially in elevation and partially in section, of a tank with my invention applied thereto; and

Fig. 2 is a similar view of a modification of the valve structure.

Referring particularly to Fig. 1, a tank 1, which may be that of a transformer, circuit breaker or other electrical apparatus, is provided with a quantity of insulating oil, indicated at 2. The illustration of the electrical apparatus is omitted as being unnecessary to an understanding of the present invention. A space 3, above the oil, is filled with an inert gas, as will be hereinafter set forth.

A vent 4 in the transformer wall is adapted to be connected to the atmosphere by means of a pipe 5, a respirator 6, a pipe 7 and a valve structure 8, which comprises a hollow piston 9 that is closed at one end. The piston 9 is provided with openings 11 and 12 that are adapted to register with the opening of pipe 7, as will be hereinafter described.

90 The pipe 5 is also connected to a U-tube 13, having an enlarged outer end 14. The tube 13 is filled with a suitable liquid, such, for example, as mercury, which supports a hollow float member 15 that is mechanically connected to the piston 9. The float 15, which is provided with a removable cap 16, may contain mercury or other suitable liquid or material in desired quantity to determine the pressure at which the valve mechanism operates.

95 The respirator 6 is provided with a suitable material for rapidly deoxygenating and dehydrating air passing therethrough, the resulting product being substantially pure dry nitrogen.

The space 3 in the transformer tank 1 may be initially filled with nitrogen in any suitable manner. For example, the tank may be substantially filled with oil, a valve 17 being closed to prevent the oil entering the valve mechanism. It may be assumed that oil has been withdrawn from the tank by means of the usual drain cock (not shown), until the level of the oil is below the vent 4. The pressure within the tank is then below atmospheric pressure, and the column of liquid in the portion 14 of the U-tube 13 has fallen to such level that the opening 11 in the piston 9 registers with the pipe 7. Air then enters the upper end of the valve 8 and passes through the piston 9, opening 11, pipe 7 and respirator 6. Substantially pure nitrogen flows through pipe 5 to the space 3 of the tank. Accordingly, the space 3 is occupied by an inert gas (nitrogen) that is substantially free from moisture. The level of the oil under normal temperature conditions may be determined by the amount withdrawn from the tank.

When the transformer or other apparatus is in operation, its temperature increases by reason of the electrical losses in the heating of the windings. The volume of the oil 2 increases correspondingly, and the gas within the space 3 is placed under pressure. The pressure of the gas correspondingly affects the height of the column of mercury in the tube 13 to vary the position of the float 15 and the piston 9. When the pressure in the tank reaches a desired predetermined value, the opening 12 registers with the opening in the pipe 7, and gas is permitted to escape therethrough. The predetermined pressure may be of any desired value, but it is preferably not to exceed five pounds per square inch in order that the seams of the containing tank may be not be opened.

When the temperature of the oil 2 decreases and the pressure in the tank falls below atmospheric pressure, the float 15 and the piston 9 move downwardly and, when the pressure falls to a predetermined value, air is admitted through the opening 11 in the manner previously described in connection with the initial preparation for operation. The valve mechanism is preferably adapted to operate when the pressure in the tank is only slightly below atmospheric pressure in order that air may not be drawn through seams of the tank.

From the foregoing, it will be apparent that the pressure within the tank may be relieved at any desired value and that an inert gas may be supplied to the tank when the pressure is below atmospheric pressure by any desired amount.

Reference may now be had to Fig. 2, in which a modification of the valve mechanism is illustrated and in which similar reference numerals are employed to designate like

parts. The essential difference between the valve mechanism of Fig. 2 and that of Fig. 1 is the substitution of a movable weight member 19 for the hollow piston 9 in Fig. 1. The valve member 19 is connected to an intermediate portion of a lever arm 20 that has a lost-motion connection at one end to a stationary member 21 and that is connected at its other end to a float member 15. A stop member 22 serves as a fulcrum for the lever 20 when the float member 15 falls by reason of decreasing pressure within the tank.

When the pressure within the tank increases, the float member 15 raises the outer end of the lever 20. When the inner end of the lever 20 rests in the lower portion of a slot 23 with which the upright member 21 is provided, further upward movement of the lever 20 raises the valve member 19 to open the pipe 24.

When the pressure within the tank decreases and the float 15 falls in accordance therewith, permitting the valve member 19 to close the opening in pipe 24 and, in case the pressure continues to fall, the lever 20 is actuated about its point of pivotal connection to the valve member 19 until it engages the pin 22. Further downward movement of the float member 15 causes the lever 20 to move about the pin 22 as a fulcrum and, when the lever 20 is in the position indicated by a dotted line, to again lift the valve member 19 from its seat. The pin-and-slot connection to the member 21 permits this movement. It will be observed that the operation of the modified form of my invention is similar in principle to that of the mechanism of Fig. 1.

The principal advantages of my valve mechanism are that it is simple in construction and the single controlling mechanism operates to control communication of the tank with the atmosphere when the pressure in the tank is either above or below atmospheric pressure.

It will be understood that the respective pressures at which the valve mechanism operates may be adjusted as desired by varying the relative positions of the ports in the valve member and the opening in the communicating pipe, by varying the initial height of the column of liquid in the U-tube or the dimensions of the various parts, and by varying the weight of the float member by varying the quantity or nature of the material therein.

I claim as my invention:

1. The combination with a tank having a vent, of means for opening said vent when the fluid pressure in said tank exceeds a predetermined value or is below a second and lower predetermined value, said means comprising a movable member having ports for communicating with said vent.

2. The combination with a tank having a vent, of means for opening said vent when the fluid pressure in said tank exceeds a predetermined value or is below a second and lower predetermined value, said means comprising a movable member, and pressure-responsive means for controlling said movable member.
3. The combination with a tank having a vent, of means for opening said vent when the fluid pressure in said tank exceeds a predetermined value or is below a second and lower predetermined value, said means comprising a movable member, and a column of liquid for controlling the position of said member.
4. The combination with a tank having a vent, of means for opening said vent when the fluid pressure in said tank exceeds a predetermined value or is below a second and lower predetermined value, said means comprising a pressure-responsive body of liquid and a float member.
5. The combination with a tank having a vent, of means for opening said vent when the fluid pressure in said tank exceeds a predetermined value or is below a second predetermined value, said means comprising a pressure-responsive body of liquid and a tubular float member having lateral openings therein for communicating with said vent.
6. The combination with a container having an opening, of means for closing said opening when the pressure within said container is within predetermined limits and for uncovering said opening when the pressure is without said limits, said means comprising a movable member having a plu-
- riality of openings for registering with the opening in said container.
7. The combination with a tank containing a fluid, of means for connecting said tank to the atmosphere when the pressure therein exceeds or falls below atmospheric pressure by predetermined different amounts, said means comprising a pressure-responsive valve member.
8. The combination with a tank having a vent, of means for controlling said vent comprising a column of liquid responsive to pressure within said tank and a valve member floating on said liquid and operable to open said vent when the height of said column is above a predetermined level and is below a second and lower predetermined level.
9. The combination with a tank having a vent, of means for controlling said vent in accordance with maximum and minimum pressure conditions within said tank, said means comprising a U-tube having liquid therein and having its respective ends connected to said tank and to the atmosphere and a valve member controlled in accordance with the height of a column of liquid in said tube.
10. The combination with a tank and de-oxidizing means communicating therewith, of means comprising a float-controlled valve member for connecting said deoxidizer to the atmosphere under predetermined maximum and minimum pressure conditions in said tank.

In testimony whereof, I have hereunto subscribed my name this 26th day of April 1923.

CLARENCE J. RODMAN.
